(57) **CLAIM**

The ornamental design for a bottle, as shown and described.

DESCRIPTION

FIG. 1 is a perspective view of a first illustrative embodiment of the bottle;
FIG. 2 is a front view of the bottle in FIG. 1;
FIG. 3 is a rear view of the bottle in FIGS. 1-2;
FIG. 4 is a left side view of the bottle in FIGS. 1-3;
FIG. 5 is a right view of the bottle in FIGS. 1-4;
FIG. 6 is a top view of the bottle in FIGS. 1-5;
FIG. 7 is a bottom view of the bottle in FIGS. 1-6;
FIG. 8 is a perspective view of a second illustrative embodiment of the bottle;
FIG. 9 is a front view of the bottle in FIG. 8;
FIG. 10 is a rear view of the bottle in FIGS. 8-9;
FIG. 11 is a left side view of the bottle in FIGS. 8-10;
FIG. 12 is a right view of the bottle in FIGS. 8-11;
FIG. 13 is a top view of the bottle in FIGS. 8-12;
FIG. 14 is a bottom view of the bottle in FIGS. 8-13;
FIG. 15 is a perspective view of a third illustrative embodiment of the bottle;
FIG. 16 is a front view of the bottle in FIG. 15;
FIG. 17 is a rear view of the bottle in FIGS. 15-16;
FIG. 18 is a left side view of the bottle in FIGS. 15-17;
FIG. 19 is a right view of the bottle in FIGS. 15-18;
FIG. 20 is a top view of the bottle in FIGS. 15-19;
FIG. 21 is a bottom view of the bottle in FIGS. 15-20;
FIG. 22 is a perspective view of a fourth illustrative embodiment of the bottle;
FIG. 23 is a front view of the bottle in FIG. 22;
FIG. 24 is a rear view of the bottle in FIGS. 22-23;
FIG. 25 is a left side view of the bottle in FIGS. 22-24;
FIG. 26 is a right view of the bottle in FIGS. 22-25;
FIG. 27 is a top view of the bottle in FIGS. 22-26; and,
FIG. 28 is a bottom view of the bottle in FIGS. 22-27.
The broken lines in the drawings illustrate the portions of the bottle that form no part of the claimed design.
